UNITED STATES PATENT OFFICE.

JOSEPH JEFFERSON, CORNELIUS JEFFERSON, LAZARUS JEFFERSON, AND MORDECAI JEFFERSON, OF BRADFORD, COUNTY OF YORK, ENGLAND.

MACHINE FOR WASHING FIBERS.

SPECIFICATION forming part of Letters Patent No. 286,305, dated October 9, 1883.

Application filed March 16, 1883. (No model.) Patented in France June 28, 1882, No. 137,652, and in Belgium June 28, 1882, No. 58,333.

To all whom it may concern:

Be it known that we, JOSEPH JEFFERSON, CORNELIUS JEFFERSON, LAZARUS JEFFERSON, and MORDECAI JEFFERSON, subjects of Her Britannic Majesty Queen Victoria, and residents of Bradford, in the county of York, England, have invented new and useful Improvements in Machinery for Washing Fibers, (for which we have obtained patents in France, No. 137,652, dated the 28th day of June, 1882, for fifteen years, and in Belgium, No. 58,333, dated the 28th day of June, 1882, for fifteen years,) of which the following is a specification.

This invention relates to an improved construction and combination of mechanism to be employed on machines for washing wool and other like fibers, whereby the fibers under operation are passed or forwarded to the nip of the squeezing-rollers, and the said rollers are so arranged as to first nip and squeeze the fiber when the latter is in the water, and then impart the finishing or dry nip above water-level. We attain these objects by mechanism illustrated in the accompanying drawings, in

25 which—

Figure 1 is a vertical section of part of the washing trough or bowl, showing the squeezing-rollers and improved fork for forwarding the fiber to the nip of the said rollers. Fig. 2 is a plan view, partly in section, of Fig. 1. Figs. 3, 4, 5, and 6 are views of parts separated.

Similar letters refer to similar parts throughout the several views.

A is the washing-bowl; B, the ordinary fork; C, the incline; D, the squeezing-rollers, arranged, as shown, so that the first nip is below the water-level, the second or dry nip above the water-line. The upper roller, D, is covered with a layer of elastic material, so as to be a squeezing-roller. E F G H are forks hung, respectively, on rods I, and free to oscillate thereon. The rods I are bolted to and revolve with two disks, J K, between which disks said forks E, F, G, and H are suspended. The disks J K have outwardly-projecting tubular bosses L L, that revolve in tubular sockets a,

which are formed on brackets M M. These brackets are fastened to the walls of the bowl or vessel A. The disk J has apertures b (see Fig. 6) and the disk K has notches c (see Fig. 5) for the reception of the rods I, which are secured to said disks by the screw-bolts d. Secured in the boss L of the disk J is the driving-shaft N, which, when revolved by suitable means, rotates the disks J and K, which in turn carry the rods I and forks E F G H around with them. Through the boss L of the disk K and through said disk passes a bolt, e, which, by a set-screw, f, or other means, is held fastened to the socket a, in which said boss revolves. This stationary bolt e carries near the inner face of the disk K a stationary cam, O. To this cam O is pivoted an L-shaped tappet, S, which is crowded outward by a spring, g, the play of said spring being controlled by a bolt, h. As the disks revolve, arms P of the forks E F G H, carrying anti-friction rollers Q, come in contact successively with a stationary guide, R, and then with the cam O, as shown by fork H in Fig. 1. The forks E, F, G, and H are fastened to tubes i, which surround the rods I, and turn loose thereon. To these tubes the arms P are also rigidly fastened. After the rollers Q leave contact with the fixed guide R, the disks revolving in the direction of the arrow 1, the said rollers come in contact first with the lower side of the stationary cam O, and then with the tappet S, as shown by fork E in Fig. 1. By this motion the point of the fork E is caused to carry and deliver the fiber to the front or wet nip of the rollers D. The point or end of the fork then bearing on or against the top roller, D, is carried up until all the parts assume the position shown by the fork F in Fig. 1. Each arm P has an adjusting-slot for fixing the position of the roller Q in relation to the cam O, whereby the traverse of the point of the fork to the nip is accurately adjusted.

We are aware that prior to our invention swing-forks—such as B—had been used for the purpose of passing wool or fiber to the squeez-

ing-rollers of fiber-washing machines, and to such forks we make no claim as our invention.

We claim—

1. The combination of forks E F G H with the disks J K, arms P, and friction-rollers Q, and with the stationary cam O, having tappet S between said disks, substantially as herein shown and described.

2. The loosely-suspended forks E F G H, combined with the disks J K, arms P, rollers

Q, guide R, cam O, tappet S, and rollers D D, substantially as herein shown and described.

JOSEPH JEFFERSON.
CORNELIUS JEFFERSON.
